US00D822711S

(12) **United States Design Patent** (10) Patent No.: **US D822,711 S**
Bachman et al. (45) Date of Patent: **** Jul. 10, 2018**

(54) **DISPLAY SCREEN OR PORTION THEREOF WITH GRAPHICAL USER INTERFACE**

(71) Applicant: **Apple Inc.**, Cupertino, CA (US)

(72) Inventors: **William Martin Bachman**, San Jose, CA (US); **Colin Bennett**, San Francisco, CA (US); **Alan C. Dye**, San Francisco, CA (US); **Alexander C. D. Fringes**, San Francisco, CA (US); **Monika E. Gromek**, Oakland, CA (US)

(73) Assignee: **Apple Inc.**, Cupertino, CA (US)

(**) Term: **15 Years**

(21) Appl. No.: **29/606,435**

(22) Filed: **Jun. 5, 2017**

(51) LOC (11) Cl. **14-04**

(52) U.S. Cl.

USPC **D14/487**

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The dashed broken lines in the FIGURE show a display screen or portion thereof, and form no part of the claimed design.

The dot-dash broken lines in the FIGURE and the areas within the dot-dash broken lines show portions of the graphical user interface that form no part of the claimed design.

1 Claim, 1 Drawing Sheet
